H. W. PATRICK.
SHOWER BATHING APPARATUS.
APPLICATION FILED MAY 10, 1919.

1,318,172.

Patented Oct. 7, 1919.

INVENTOR:
HENRY W. PATRICK

ATTORNEYS

UNITED STATES PATENT OFFICE.

HENRY W. PATRICK, OF MANSFIELD, OHIO.

SHOWER-BATHING APPARATUS.

1,318,172.

Specification of Letters Patent.

Patented Oct. 7, 1919.

Application filed May 10, 1919. Serial No. 296,110.

To all whom it may concern:

Be it known that I, HENRY W. PATRICK, a citizen of the United States, resident of Mansfield, county of Richland, and State of 5 Ohio, have invented new and useful Improvements in Shower-Bathing Apparatus, of which the following is a specification, the principle of the invention being herein explained and the best mode in which I have 10 contemplated applying that principle, so as to distinguish it from other inventions.

My invention relates to shower bathing apparatus and particularly to apparatus of this character designed as an attachment to 15 the ordinary bath tub. It is particularly designed by this invention to provide a device of this character which shall be of simple and durable construction and efficient in operation. The apparatus is, furthermore, 20 portable, holds the spraying portion thereof a slight distance from the body so as to obviate any blocking of the spraying openings without giving any shock to the body by water falling or striking the same from a distance, is provided with means for conveniently testing the water, and with means for 25 giving a close approximation to the neck when in use, and enables a satisfactory bath to be taken without the necessity of wetting 30 the hair.

The annexed drawing and the following description set forth in detail certain means embodying my invention, the disclosed means, however, constituting but one of the 35 various mechanical forms in which the principle of the invention may be applied.

In said annexed drawing:

Figure 1 represents a front elevation disclosing my improved shower bathing apparatus in use;

Fig. 2 represents a front elevation, upon an enlarged scale, of portions of said apparatus when not in use, some parts being shown in section;

Fig. 3 is a vertical section taken in the plane indicated by the line III—III, Fig. 2;

Figs. 4 and 5 represent, respectively, vertical sections taken in the planes indicated by the lines IV—IV and V—V, Fig. 2;

Fig. 6 represents an elevation of one of 50 the connecting elements;

Fig. 7 represents an elevation of a valve portion utilized for conveniently testing the water;

Fig. 8 represents a side elevation of fragmentary portions of the apparatus in use;

Figs. 9 and 10 represent, respectively, perspective and vertical sectional views of a suitable bearing member by means of which the apparatus closely approximates the neck 60 when in use and is kept from any undue tilting at the rear due to the tendency to pull downwardly at the front.

Referring to the annexed drawing, a section of tubing is illustrated by the ordinal 65 1, the same being comprised of any suitable material which shall have the characteristics of rubber mixed with proper ingredients so as to produce an element having some rigidity with its flexibility. This tubing 1 is bent 70 to form a curved member inclosing any suitable area, the tubing 1 in the inclosed drawing being shown, for purposes of illustration, as bent to fit the shoulders of the user. By suitable connecting elements 2, Fig. 6, 75 the two ends of said tubing 1 are connected to a pair of tubing sections 3, of the design plainly shown in Fig. 2. The respective outer ends of the sections 3 are connected to a common tubing section 4 which in turn 80 communicates with a tubing section 7 adapted to be secured to the faucet 8 of an ordinary bath tub 9. The tubing section 4 is formed to receive a suitable valve 5, preferably rubber, secured to a stem member 6, 85 said valve 5 being provided with an opening 5' adapted in a certain position of the valve to provide a passage for water between tubing sections 3 and 7. One side of the tubing section 4 is intersected by an opening 4' 90 adapted in a certain position of the valve 5 to register with the opening 5', the tubing 7, at the same time, communicating with an opening 5² formed in the valve 5 and intersecting the opening 5'. This valve 5 and the 95 allied parts are provided for the purpose of conveniently testing and regulating the water. It is evident that the apparatus being

in position upon the user, and the opening 5² set to register with the tubing section 7, that the water from the faucet 8 will be discharged from the opening 4' and will not 5 have access to the tubing sections 3. The water thus issuing from the opening 4' can be tested by the hand for temperature and the proper adjustment of the temperature secured before the valve 5 through the stem 10 portion 6 is given a quarter of a turn, whereby the opening 4' will be shut off and the water allowed to pass straight through the opening 5' of the valve 5 from the tubing section 7 to the tubing sections 3.

15 In order that the tubing 1 may be conveniently fitted upon or removed from the shoulders of the user, and may be adjusted thereon as desired, preferably so that the apparatus will closely approximate the neck 20 of the user, a block 10 is provided, of suitable material, preferably rubber, formed with openings 10' for the tubing sections 3. Said block is movable longitudinally of said sections 3 so as to vary as desired the angle 25 included between said diverging sections 3, the block when in use preferably being positioned, as plainly shown in Fig. 1, so that the apparatus will closely approximate the neck of the user. The block 10 serves a further and very important function in that 30 the same provides a bearing, as plainly shown in Fig. 8, whereby the tendency of the apparatus to pull downwardly in front and thereby unduly tilt the rear portions 35 thereof, is obviated, the block tending to produce a pull horizontally outwardly from the user, rather than a vertical pull downwardly. This tendency produced by the block 10, particularly when said block is 40 formed of naturally adhering material such as rubber, also prevents the block from accidentally slipping downwardly upon the tubing sections 3 and unduly loosening the apparatus from the neck of the user. The tubing 1 is formed with suitable spray openings 45 11. In order to hold the tubing to its shape, as well as effectually to prevent the water from splashing upon the hair and face of the user, I vulcanize or mold, or otherwise 50 suitably secure, to the upper face of the tubing 1 a rubber shield or canopy 12, the same being formed with a suitable neck receiving opening 14, the wall of which opening is 55 formed by a bead 13 suitably secured to the edge of the shield 12. This bead 13 gives rigidity to the web 12 and prevents the tearing of the same. The position of the spray openings 11, as plainly seen in Figs. 4 and 60 5, enables the tubing to hold the spraying apparatus slightly off the shoulders of the user so as to prevent the blocking of said spray orifices.

What I claim is:

1. Shower bathing apparatus comprising,

perforated tubing formed to fit the shoulders of the user combined with a shield or canopy secured to said tubing, interiorly of the latter, and formed with a neck-receiving opening.

2. Shower bathing apparatus comprising, 70 perforated tubing formed to fit the shoulders of the user combined with a shield or canopy vulcanized or otherwise suitably secured to said tubing, disposed interiorly of the latter, and formed with a neck-receiving 75 opening bounded by a reinforcing bead.

3. Shower bathing apparatus comprising, 80 perforated tubing bent to inclose a suitable area combined with a shield or canopy secured to said tubing, covering said area, and formed with a neck-receiving opening bounded by a reinforcing bead secured to the edge of said shield.

4. Shower bathing apparatus comprising, 85 perforated tubing bent to inclose a suitable area, a neck-receiving member secured to said tubing, a tubing section adapted to be secured to the source of water supply, means for connecting said perforated tubing and said tubing section, and means providing a 90 bearing for the front portion of said perforated tubing when in use for obviating the tendency of the rear portion of said perforated tubing to tilt upwardly, due to the downward pull of said tubing section and 95 allied parts.

5. Shower bathing apparatus comprising, 100 perforated tubing bent to inclose a suitable area, a neck-receiving member secured to said tubing, a tubing section adapted to be secured to the source of water supply, a pair of diverging tubing sections, means providing communication between said pair of tubing sections and said tubing section, means connecting said pair of sections and 105 said perforated tubing, and means, including a bearing member, for varying the included angle between said pair of sections.

6. Shower bathing apparatus comprising, 110 suitable perforated tubing formed to fit the shoulders of the user, a neck-receiving bead secured to said tubing, a tubing section adapted to be secured to the source of water supply, a pair of diverging tubing sections, a common connection between said tubing 115 section and said pair of sections, means providing communication between said pair of tubing sections, respectively, and the ends of said perforated tubing, and means for varying the included angle between said pair 120 of sections.

7. Shower bathing apparatus comprising, 125 perforated tubing bent to inclose a suitable area, a tubing section adapted to be secured to the source of water supply, a second tubing section adapted to communicate with said first-mentioned tubing section, a valve secured within said second-mentioned

tubing section and provided with a stem intersecting the latter, and a pair of diverging tubing sections both adapted to communicate at one end with the valve contained within 5 said second-mentioned tubing section and at their other ends, respectively, with the ends of said perforated tubing, said second-mentioned tubing section being formed with an opening intersecting its lateral surface and 10 communicating with the interior valve space,

and said valve being formed with a continuous longitudinal bore and with a lateral opening intersecting said longitudinal bore and adapted in a certain position to communicate with said first-mentioned tubing 15 section and in another position to communicate with the opening in said second-mentioned tubing section.

Signed by me, this 7th day of May, 1919.

HENRY W. PATRICK.
